UNITED STATES PATENT OFFICE

MARCEL MENNESSON, OF NEUILLY-SUR-SEINE, FRANCE, ASSIGNOR TO THE SOCIETE ANONYME SOLEX, OF NEUILLY-SUR-SEINE, FRANCE

CARBURETOR

Application filed April 9, 1930, Serial No. 442,916, and in Belgium May 25, 1929.

The present invention relates to temperature operated fluid flow controls and, more especially, to controls adapted for use in carburetors.

5 One of the objects of the invention is to provide means operative to control the flow of a fluid in a conduit as a function of a temperature.

Another object is to provide a carburetor 10 assembly in which a supplementary flow of air is introduced in quantities which are a function of the temperature of the motor water-jacket, the exhaust gases, the lubricating oil, or of the air in the vicinity of 15 the motor, as desired.

Further objects will appear in the course 20 of the detailed description now to be given with reference to the accompanying drawing, in which the single figure represents one 25 illustrative embodiment of the invention.

Referring to the drawing, there is shown a carburetor assembly composed of a nozzle *e* of conventional design supplied with fuel from a constant level chamber,—a mixing 30 chamber *f* fitted with a throttle valve,—a supplementary air inlet conduit *g*,—a valve *h* controlling the inlet end of conduit *g* and fitted with a stem *i* carrying a cross-piece or piston *j*,—a spring *h*¹ opposing displacement of valve *h*,—a "spider" *h*² serving as abutment for spring *h*¹,—a cylinder *k* of somewhat larger section than element *j* and containing a substance whose viscosity varies considerably as a function of the temperature 35 (grease, heavy oil, vaseline or mixtures thereof, elements *j* and *k* constituting a dashpot,—and a jacket *k*¹ adapted to receive circulating fluid (1) from the motor water-jacket (2) from the oil circulating system 40 or (3) from the motor exhaust.

The operation of the device is practically evident from an inspection of the drawing. If substance *b* be chosen to be solid at ordinary temperatures or if it have a high viscosity without being solid, element *j* will meet with a high resistance in moving therethrough and, when the motor is cold, valve *h* will not open. Contrariwise, as the motor 45 warms up, the viscosity of substance *b* de-

creases and valve *h* is lifted by the suction of the motor transmitted via mixing chamber *f* and conduit *g*. A supplementary supply of air will thus be admitted to the motor.

Obviously the use of jacket *k*¹ is optional. 55 If not used, substance *b* will merely respond to the temperature variations adjacent the carburetor. When cooling fluid from the motor, lubricating oil, or exhaust gases are circulated therethrough, the carburetor will be supplied with extra air as a function of temperature variations of the particular fluid circulating in the jacket. 60

It is to be understood that the invention is not limited to carburetors but may be applied 65 to any combination in which the section of a part is to be controlled as a function of a given temperature change.

What I claim is:—

In combination with a carburetor assembly including a mixing chamber, a nozzle positioned to supply fuel to said mixing chamber, an air supply conduit positioned to communicate at opposite extremities with said mixing chamber and with the atmosphere, a valve positioned in said air supply conduit and controlling communication between the inside of the latter and the atmosphere, and a spring tending to move said valve into closed position, means for controlling movement of said valve comprising a stem attached thereto, a container, and a substance solid at ordinary temperatures and liquefying when heated, said substance being mounted in said container and contacting with said stem, whereby when the said substance is in the solid state it presents the opening of the valve but heating of said substance liquefies the latter so as to release said stem and permit said valve to open under the action of the suction in the mixing chamber of the carburetor. 70 75 80 85 90

In testimony whereof I affix my signature.
MARCEL MENNESSON. 95
